[57] CLAIM

The ornamental design for a support base for a desk set
or similar article, as shown and described.

DESCRIPTION

FIG. 1 is a top perspective view of a support base for a
desk set or similar article showing my new design in the
form of a paper weight;

FIG. 2 is a top plan view;

FIG. 3 is a front elevational view;

FIG. 4 is a rear elevational view;
FIG. 5 is a left side elevational view, the right side being
a mirror image thereof;

FIG. 6 is a bottom plan view; and

FIG. 7 is a top perspective view of a second embodiment
of my new design in the form of a writing instru-
ment holder.
